WILLIAM F. JACOBS, OF OTTAWA, ILLINOIS, ASSIGNOR TO J. E. PORTER COMPANY, OF OTTAWA, ILLINOIS, A CORPORATION OF ILLINOIS.

BARN-DOOR TRACK.

1,199,185.

Specification of Letters Patent. Patented Sept. 26, 1916.

Application filed February 23, 1915. Serial No. 9,829.

To all whom it may concern:

Be it known that I, WILLIAM F. JACOBS, a citizen of the United States, and a resident of Ottawa, in the county of La Salle and 5 State of Illinois, have invented certain new and useful Improvements in Barn-Door Tracks; and I do hereby declare that the following is a full, clear, and exact description thereof, reference being had to the accompanying drawings, and to the letters of 10 reference marked thereon, which form a part of this specification.

This invention relates to improvements in barn door tracks, and more particularly to 15 the construction of barn door tracks embodying a plurality of track sections forming a protective hood or covering for the door hanger and the track proper or tread portion.

20 The principal features of my invention are directed to the construction of the track-supporting member, the manner of mounting the track thereon, and to the means for supporting and joining the several sections constituting the complete track. These and 25 other features of my invention will be pointed out as I proceed with the description of the construction of the parts constituting the barn door track embodying the 30 features of my invention and in connection with the accompanying drawings, in which—

Figure 1 is a fragmentary view in elevation of portions of the track, showing a 35 bracket supporting the ends of the adjacent track sections; Fig. 2 is an enlarged view in vertical section, taken on line 2—2 of Fig. 1; Fig. 3 is a view in end elevation, showing the end plates and bracket supporting the 40 end of the track; and Fig. 4 is a view in vertical section, taken on line 4—4 of Fig. 3, showing the construction of the end plate.

The barn door track, as shown in the accompanying drawings, and embodying the 45 several features of my invention, comprises, in general, a track-supporting member 10 formed to provide a protective covering for the door hanger and adapted to be secured to the wall 11 of a building immediately 50 above the opening to be closed by a sliding door, and a track member or tread portion 12, mounted on said supporting member and forming the bearing surface adapted to be engaged by the rollers of the door hanger. 55 To afford ease and convenience in shipment

and manipulation, the track preferably consists of several sections joined end to end, there being provided a plurality of brackets 13, also adapted to be secured to the wall 11 of the building, and to engage and support 60 the abutting ends of the track sections.

Referring now more in detail to the formation of the track, and particularly the construction of one of the track-supporting members 10, the same is preferably 65 constructed of sheet metal, bent to the desired shape. As shown in Fig. 1, said supporting member is provided along its upper marginal portion with a comparatively narrow flange 14, adapted to be placed against the 70 wall 11, and through which means for attaching the sections to the wall extend, as for instance screws 14^b, spaced apart at suitable intervals and acting to secure the track-supporting member to the building. The 75 extreme upper marginal portion of the flange 14 is preferably reduced in thickness and bent inwardly toward the wall to a slight degree, as shown at 14^a, to provide a sharp margin adapted to be embedded into 80 the wall when the sections of the track are applied to the wall, thereby affording a tight and water-proof joint between the sections and the wall, to prevent the leakage 85 of water between the coating surfaces of the flange and said wall.

From the lower margin of the vertical flange 14, the section is bent outwardly to provide an upper wall portion 15, integral with said flange 14 and inclined downwardly 90 at a slight angle. From the outer end of the outwardly inclined portion 15 the section continues in a downwardly direction, forming a vertical portion 16 extending vertically from the outer end of said outwardly 95 inclined portion 15 parallel with and spaced from the wall 11 of the building. At the lower end of said vertical portion 16, the section is again bent to provide an inclined portion extending inwardly and toward the wall 11, the angle of inclination being approximately 45°. This portion is comparatively short in length, thereby providing a comparatively wide space between its lower extremity and the wall 11. The lower portion of the section terminates in an outwardly and downwardly, marginal portion 18, extending from the lower extremity of the inwardly inclined portion 17, the inclination of said lower marginal portion being 110

also approximately 45° and obtained by bending the lower marginal portion of the section in a reverse direction from the inwardly inclined portion 17 immediately above.

- 5 Attached to the inwardly and upwardly facing surface of the inclined portion 17, is the before mentioned track member or tread portion 12, consisting preferably of an angle bar, having web portions unequal in length and meeting at an angle of 45°. The longer of said web portions is adapted to lie flat against the inner surface of the inclined portion 17, and to be securely attached thereto in any suitable manner, preferably by welding the parts together. The longer web portion projects inwardly beyond the lower extremity of the inclined portion 17 to which it is fixed, and, since the surface thereof is 10 inclined downwardly, the two web-members of the angle bar are so disposed as to form an upwardly facing, V-shaped groove or channel, constituting a bearing or tread surface, disposed inwardly from the adjacent portion of the track-supporting member, and adapted to be engaged by the rollers 20 of the door hanger 21, there being provided a suitable number of said hangers secured to the upper margin of the door 22, 15 which is suspended from the hangers in a manner to be moved lengthwise upon the track through the medium of said rollers. The door hanger 21 is preferably constructed as follows: The roller 20 is mounted on a journal 23, to which is rigidly connected a downwardly extending connecting member 24, mounted at the end of the journal adjacent to the inner face of the roller, and pivotally connected at its lower end, below 20 the track member 12, to a yoke 25 secured to the upper margin of the door 22 by suitable bolts 26. The connecting member 24 is curved inwardly from the vertical plane of the roller to clear the inner margin of the track member, and immediately below the tread member the same is inclined toward 25 said plane of the roller, thereby permitting the point of pivotal connection between the connecting member and the yoke to be located within the vertical plane of the roller. The upper surface of that portion of the connecting member 24 immediately below the track 12 is provided with two intersecting surfaces forming an upwardly facing, 30 V-shaped groove or notch 24a corresponding in shape to, and spaced a short distance from, the under surface of the track member, the vertex of said V-shaped groove lying substantially in the vertical plane of 35 said roller. The inclined surfaces of the V-shaped groove 24a are normally disposed in parallel relation to the under surfaces of the track members, and are adapted to engage the adjacent surfaces of the track 12, 40 when the door is swung laterally or moved 45

upwardly to such extent as would displace the roller from the track member. In this manner the construction of the connecting member provides means whereby the roller or rollers are maintained within the groove 70 of the track, thus avoiding the danger of breakage of the parts or the inconvenience and labor of replacing the roller upon the track.

As before stated, the track-supporting member comprises a plurality of sections of suitable lengths joined end to end to form a complete track of the desired length, the ends of the sections being joined and supported by means of the brackets 13. Referring to the construction of one of the brackets 13, the same consists preferably of cast metal, having a body member 27 of a thickness substantially equal to that of the track-supporting member 10, and formed to 75 correspond with the contour of the outer surface of said supporting member. The bracket is adapted to fit against the outer surface of the supporting member, and is of sufficient width to overlap the end marginal portions of the abutting sections on either side of the joint. Extending longitudinally of, and substantially throughout the length of, the bracket, there is provided a stiffening rib 28, located intermediate the 80 lateral margins of the body member 27 of the bracket and projecting outwardly therefrom, the outer margin of said rib following substantially the general contour of the bracket. The bracket is provided at its 85 lower end with a hooked extremity 29 adapted to receive the lower end marginal portions of the abutting sections, and at its upper end is provided with two circular bosses 30, 30, located on either side of the 90 center line of the bracket, in which are provided holes through which extend screws 31, 31, extending through holes formed adjacent to the ends of the marginal flanges 14 of the abutting sections, and anchored in 95 the wall 11. In this manner the bracket serves to connect the ends of the sections and to maintain the same in perfect alignment, and further to support the track by its connection with the building through the medium of the screws 31. At a point intermediate and substantially midway of the upper and lower ends of the bracket, are provided two horizontally disposed holes 100 32, 32, the same being in vertical alignment 105 with the bosses 30, 30 at the upper end of the bracket, and preferably formed within circular bosses 33, 33 adjacent to the lateral margins of the bracket. The rib 28 is preferably divided into two parts or branches 110 throughout the portion thereof adjacent to the holes 32, 32, the branches extending laterally to and terminating at the bosses 115 33, 33, as shown in Fig. 1, the branches of the upper portion of the rib preferably 120

terminating in the form of small semi-circular flanges 34, 34, projecting outwardly above the holes, said flanges serving to prevent the entrance of water and foreign materials into the holes from above. These holes constitute means for supplying lubricant to the track member 12 and to the roller journals, this being accomplished by inserting the nozzle of an oil-can through 10 said holes. The central rib 28 is obviously adapted to afford increased strength and rigidity to the bracket to prevent the same from being distorted by reason of the vertical strain to which it is subjected, particularly throughout the portion immediately 15 above the outwardly inclined portion 15 of the track-supporting member.

The provision of two oil holes, located as above described, is preferred for the following reason: In constructing the track sections, it is desirable that all of such sections be constructed uniformly as regards the location and spacing of the holes, which are punched at the time the sections are formed 25 and prior to the assembly of the sections to form the completed track. As will herein-after appear, this construction not only reduces the cost of manufacture, but avoids the necessity of making such holes during 30 the application of the sections and brackets to the building. It is therefore preferable to provide, at the ends of each section and a short distance inwardly from the end margins, two vertically aligned holes, one adjacent to the upper margin and the other approximately midway of the upper and lower margins of the sections. Thus, when two 35 sections are placed in position end to end and a bracket applied to support the ends of the sections, there are provided at the joint two sets of holes, the uppermost set adapted to register with the screw holes and the lower set with the oil holes of the bracket. In this manner, the upper holes at the ends 40 of the abutting sections serve as screw holes and the lower holes as apertures for the purpose of introducing oil, as before set forth. On the other hand, when one end of a section is also the end of the track, means 45 other than a bracket is employed for supporting the section, and thus the apertures in the track serve as screw holes, as shown in Figs. 1 and 3. By the provision of two oil holes on either side of the central line of 50 the bracket, a standard and interchangeable construction is obtained, in that the holes at the ends of the sections are so located that they will register with the screw and oil holes of the brackets, thereby avoiding the 55 necessity of forming holes in the sections during the act of assembling the track.

Referring now to the construction employed for supporting and closing the ends of the completed track, the same consists of 60 a plate 35, (Figs. 3 and 4), comprising a

thin central web portion 36 and a marginal flange 37 extending entirely about the plate, so that in section the plate resembles the section of an I-beam. In marginal contour 70 the end plate is partially irregular and conforms with the inner surface of the track-supporting section 10 and the track portion 12, and has a straight vertical margin corresponding to the surface of the wall 11. The lower margin of the end plate is provided 75 with a horizontal portion joining the vertical margin of the end plate and that portion thereof which conforms with the upper surface of the track member 12. Adjacent to the upper margin of the end plate is 80 provided a horizontal sleeve 38, formed integral with the web portion 36, having a bore therethrough extending from the front to rear, entirely through the end plate. The sleeve is preferably located within the web 85 of the end plate, so that, upon inserting the same within the end of the section with the flanged margins engaging the adjacent surfaces of the track-supporting member, the track member and the wall 11, the bore will 90 be in registering relation with the hole at the end of the section and intermediate the upper and lower margins thereof, in which position the end margin of the flange 37 of the plate and the end margin of the section 95 are substantially flush. Having inserted the plate within the end of the track with said bore and hole in registering relation, a screw 39 is inserted, the same being adapted to be anchored in the wall 11, thereby serving to 100 secure the end plate in position and to firmly attach the end of the track to the building. It is to be noted that the end plate is constructed to conform with the standard arrangement of holes at the end of the section, 105 thus enabling the same to replace a bracket for supporting the end of the track, without providing a different arrangement of the holes. The end plate serves not only as a closure for the ends of the track, but also as 110 stops or bumpers to prevent the displacement of the rollers of the door hangers from the ends of the track. The flanged construction and integral sleeve together with the stout screw, provides a rigid stop member, 115 as well as means for supporting the track in the absence of a bracket such as hereinbefore described.

The features embodied in my invention permit the practical utilization of sheet 120 metal in the construction of tracks of the character described, whereby the advantage of strength, combined with simplicity in construction and low cost of manufacture, is obtained. The feature of the track member 125 welded to the surface of the supporting member, permits the use of a single thickness of sheet metal in the formation of the latter, and avoids the necessity of sharp bends tending to weaken the structure, and 130

at the same time securing the advantage of complete protection to the door hanger and track from the effects of the weather. Furthermore, the provision of the standard arrangement of holes and standard construction for the brackets and end plates, contributes greatly to the ease and convenience with which a track may be assembled and applied to a building.

10 The several features herein set forth may be equally well obtained by modifying the details of construction and without departing from the spirit of my invention, and for that reason I do not wish to be limited to 15 the construction herein shown and described, except in so far as specifically set forth in the claims.

I claim as my invention:

1. A door hanger structure, comprising a track-supporting member made in sections, the opposed end edges of which are adapted to meet in abutting relation, each section being made of sheet metal and bent to comprise an upper flange adapted to be secured to a building wall, a web portion integral with and extending outwardly from said flange, a web portion integral with and extending downwardly from said outwardly extending web, an inclined web portion integral with and extending inwardly and downwardly from said downwardly extending web, an inclined web portion integral with and extending outwardly and downwardly from said inwardly inclined web, a trough-shaped track member located below said outwardly extending web and secured to the said inwardly inclined web, and a

bracket adapted to be secured to said wall at the joint between said sections and overlapping the meeting end portions of the latter, said bracket having an integral inclined portion extending inwardly beneath and overlapping the meeting end portions of the inwardly inclined webs to which the trough-shaped track members are secured. 40 45

2. A door hanger structure, comprising a track-supporting member made of sheet material and bent to comprise an upper flange adapted to be secured to the wall of a building, a web portion extending outwardly from said flange, a web portion extending downwardly from said outwardly extending web, an inclined web extending inwardly and downwardly from said downwardly extending web, an inclined web extending outwardly and downwardly from said inwardly inclined web, a trough-shaped track member located below said outwardly extending web and secured to said inwardly inclined web, an end plate closing the end of said track-supporting member, said end plate comprising a body portion provided with a bolt hole extending therethrough and adapted to register with a hole in said depending web, and a bolt extending through said holes 60 65 and into the wall of the building. 55

In testimony that I claim the foregoing as my invention I affix my signature in the presence of two witnesses, this 15th day of Feby., A. D. 1915.

WILLIAM F. JACOBS.
